UNITED STATES PATENT OFFICE.

LEO P. FENNESSEY, OF EDINA, MISSOURI.

LEGGING.

1,176,044.

Specification of Letters Patent. Patented Mar. 21, 1916.

Application filed August 31, 1915. Serial No. 48,275.

To all whom it may concern:

Be it known that I, LEO P. FENNESSEY, a citizen of the United States, residing at Edina, in the county of Knox and State of Missouri, have invented new and useful Improvements in Leggings, of which the following is a specification.

This invention relates to a legging of the type which is provided with a removable gaiter foldable around the exterior of the lower portion of the legging.

The primary object of the invention is to provide a legging of this character, in which the gaiter is removably connected to the legging and foldable around the exterior thereof above or below its connection with the legging.

A further object of the invention is to provide the legging and gaiter with means for securing the gaiter to the legging in such a manner as to permit the gaiter to be adjustably connected with the legging.

A still further object of the invention is to provide the legging and gaiter with fastening elements which coöperate when the gaiter is folded about the legging above its connection therewith, to maintain said gaiter in a folded condition around the upper portion of the legging.

A still further object of the invention is to provide the ends of the gaiter which meet when the gaiter is folded about the lower portion of the legging with fastening means for securing the ends of the gaiter together in such a manner that the ends may be disconnected and the strap which passes beneath the sole of the overshoes worn by the wearer of the legging, disconnected to permit said overshoes to be removed without disconnecting any portion of the body of the legging.

With these and other objects in view the invention consists in the novel combination and arrangement of parts which will be hereinafter more fully described and particularly pointed out in the claims.

The preferred embodiment of the invention has been illustrated in the accompanying drawing, although no restriction is nec-

essarily made to the precise details of construction therein shown, as changes, alterations and modifications within the scope of the claims may be resorted to when desired.

In the drawing:—Figure 1 is a side elevation of the legging and gaiter constructed in accordance with the invention, the gaiter being shown folded around the exterior of the lower portion of the legging. Fig. 2 is a similar view to Fig. 1 showing the reverse side of the legging. Fig. 3 is a view similar to Fig. 2 showing the gaiter folded about the exterior of the legging above the connection of the gaiter with the legging. Fig. 4 is a view similar to Fig. 3 showing the reverse side of the legging, from the side of the legging shown in Fig. 1. Fig. 5 is a plan view of the legging and gaiter showing the same in an unfolded condition. Fig. 6 is an enlarged side elevation of a portion of a legging and gaiter to more clearly illustrate the means for connecting the gaiter with the legging. Fig. 7 is a transverse vertical sectional view on the line 7—7 of Fig. 6.

Like characters of reference denote corresponding parts throughout the several views in the drawing.

The numeral 1 designates the legging as an entirety which comprises a body 2 and a foldable gaiter 3. The legging body 2 is of the usual construction and formed from any suitable material which is preferably waterproof and has in this instance the side edges of the body provided with a cord connection of the well known type for securing the ends of the legging together. The legging body 2 is further provided upon one side thereof adjacent the bottom edge of the legging with the usual strap 3' adapted to pass beneath the shoe of the wearer of the legging, and connected with the usual buckle 5 upon the opposite side of the legging.

The legging body 2 has secured thereto at a point substantially intermediate the top and bottom of the legging cross bars 6 and 7. The cross bar 7 is arranged adjacent the side edge of the legging, which is provided with the flexible element adapted to connect with the eyes upon the opposite side of the

legging body, while the cross bar 6 is secured to the legging body at a point which would be substantially diametrical to the cross bar 7 when the legging body is in a folded condition. The cross bars 6 and 7 are secured to the legging body in any suitable manner and their points of connection with said body may be reinforced in any manner desirable.

10 Depending from the upper top edge of the legging body are straps 8 and 9, the strap 8 being positioned in alignment with the cross bar 6, while the strap 9 is spaced from the strap 8 and provided with a buckle 10 in the upper end thereof.

15 The gaiter 3 is formed from any suitable material which may or may not correspond to the material from which the legging body 2 is formed, said gaiter conforming approximately to the shape of the lower portion of the legging body 2, which it is adapted to normally surround when in use. The gaiter 3 like the body 1 has its opposite side edges provided with means for fastening said

20 edges together when the legging is in use, and in this instance the fastening means comprises the usual flexible element and eye connection used on the side edges of the body of the legging. Secured to the lower 25 edge of the gaiter 3 is the usual buckle and strap connection, as indicated at 12, said strap passing beneath the sole of an overshoe and engaging with the buckle 13 adjacent the end of the gaiter containing the 30 flexible fastening element, when the gaiter is surrounding the lower portion of the body of the legging.

35 The upper portion of the gaiter 3 is provided with spaced slits or eyelets 14 and 15, which are normally disposed below the cross bars 6 and 7. Passing through the slits and over the cross bars 6 and 7 are straps 16, one end of which is provided with a buckle 17, with which the remaining end of the 40 strap may be adjustably connected to regulate the height of the gaiter from the lower edge of the body of the legging, said strap connections also serving to permit the gaiter to be raised and folded around the upper 45 portion of the legging body 2, when it is desired to use the legging without the gaiter covering the lower portion thereof.

50 As the gaiter portion of the legging is designed primarily to overlie the portion of the shoe of the wearer of the legging which is unprotected by an overshoe, the following description will explain the application of the legging to a person whose foot has an overshoe thereon. It will, of course, be assumed that under the conditions mentioned above, the gaiter 3 is surrounding the upper portion of the legging as indicated in Figs. 3 and 4 in the drawing, and that the strap 3' of the legging is positioned between the

55 sole of the shoe and the sole of the overshoe with the body of the legging folded and secured about the leg of the wearer. The strap 8 is first disconnected from the buckle 13 and the gaiter, after which the strap 9 is disconnected from the tongue of the buckle 10 and one end thereof removed from the slit 18 in the lower end of the gaiter adjacent the end containing the eyes for connection with the flexible element on the opposite end of the gaiter. It will now be seen 60 that the straps 16 permits the gaiter to move in a downward direction after the fastening means upon the end of the said gaiter have been unfastened. With the gaiter now in a position to be folded around the exterior of 65 the lower portion of the body of the legging, the buckle and strap connection 12 may be positioned beneath the sole of the over shoe and the flexible element engaged with the eyes upon the opposite end of the gaiter for 70 securing the same folded about the lower portion of the body.

75 It will, of course, be understood that if it is desired to remove the overshoes without removing the body of the legging which is 80 wrapped about the leg of the wearer in the usual manner, the strap 12 may be released from the buckle 13 and the fastening means for the ends of the gaiter unfastened, in order that the gaiter may be folded about 85 the upper portion of the legging and secured by the straps 8 and 9 if desired.

80 If, for any reason it should be desired to use the legging body without the gaiter, the same can be removed therefrom by disconnecting the strap 16 from the cross bars 6 and 7.

90 From the foregoing description taken in connection with the accompanying drawing it is apparent that a legging has been provided which is simple in construction, inexpensive of manufacture and highly efficient in use.

95 Having thus described the invention what is claimed as new is:—

100 1. A legging comprising a body, a gaiter surrounding the exterior of said body at the lower portion thereof, and means for removably connecting said gaiter with the body.

105 2. A legging comprising a body, a gaiter surrounding the lower portion of said body exteriorly thereof, and means for raising and lowering the gaiter removably connected with said gaiter and body.

110 3. A legging comprising a body having cross bars at opposite sides thereof, a gaiter having slits therein, and means passing through said slits and around said cross bars adapted to permit said gaiter to be 115 folded around the exterior of said body above or below said cross bars.

120 4. A legging comprising a body, cross

bars at opposite sides of said body, straps depending from the upper edge of said body in spaced relation, a garter foldable about said body above or below said cross bars and provided with fastening means engageable with said straps when said garter is folded about the body above the cross bars thereon, and means for connecting the

cross bars with the garter to permit the raising and lowering of the latter. 10

In testimony whereof I affix my signature in presence of two witnesses.

LEO P. FENNESSEY.
